UNITED STATES PATENT OFFICE.

GEORGE A. BURNHAM, OF SAUGUS, MASSACHUSETTS, ASSIGNOR TO SEARS B. CONDIT, JR., OF BROOKLINE, MASSACHUSETTS.

DOUBLE-THROW ELECTRIC SWITCH.

1,318,131.

Specification of Letters Patent.

Patented Oct. 7, 1919.

Application filed May 28, 1917. Serial No. 171,377.

To all whom it may concern:

Be it known that I, GEORGE A. BURNHAM, a citizen of the United States, residing at Saugus, in the county of Essex and State 5 of Massachusetts, have invented an Improvement in Double-Throw Electric Switches, of which the following is a specification.

This invention relates to that type of double-throw switches adapted for use in 10 manholes and similar places, and has more particular reference to the switch-operating mechanism for use with what are commonly called straight-line switches, in which the contact bearing elements move in a substantially straight line.

The invention has for its object to provide an improved switch-actuating mechanism which may be contained entirely within the switch inclosing case and having provision 20 for engagement with an external detachable operating handle; that will securely hold the switch-members in set positions until deliberately moved by an operator; that will positively insure the movement of either 25 switch-member upon operation of the other member; and that involves, structurally speaking, an improved actuating member adapted to operate both switch-members by or upon a partial rotation thereof.

30 Figure 1 is a side elevation and partial vertical section of a double-throw manhole switch embodying my invention.

Fig. 2 is an end elevation of a portion of the same.

35 Fig. 3 is a plan view of the actuating mechanism.

Figs. 4 and 5 are detail views of the actuating-mechanism.

Fig. 6 is a detail of the stirrup connecting the toggle and the lifting lever.

1 represents a suitable tank or oil receptacle, having a cover 2, and having internal lugs 3 adapted to support the main supporting plate 5 for the switch mechanism.

45 Said plate 5, as here shown, supports three sets of stationary contacts, 6, 7, and 8, disposed in parallel relation, and having suitable terminals 10, said contacts being insulated from the plate 5 by suitable bushings 9. Two sets of switch rods 11 and 12 are disposed between stationary contacts 6 and 8, and 7 and 8, respectively, and bear at their lower extremities the brush members 13 and auxiliary members 14, for en-

gagement with the stationary contacts. The 55 upper ends of said switch rods are connected to carrying frames 15 and 16, respectively. Each carrying frame with its switch rods and contact members constitutes a switch-member. A pair of like upright ears 17 are attached to the carrying frame 15, intermediate its length, and one end of a two-part lifting lever 21 is pivoted at 19 to said ears, the other end of said lever being pivoted at 23 to a bracket on the plate 5. 60

A thrust toggle, comprising two-part links, 31, 33, pivotally connected together at 35, has one of its links, as 33, pivoted at 37 to the ears on the plate 5, and its other link, as 31, is loosely connected with the 70 lifting-lever at a point near the pivotal connection of said lever with the bracket, such loose connection being here shown as a pin 29 arranged at the upper end of the link which engages a pin 25 on the lifting-lever, and 75 a stirrup 27 supported on the pin 29 and embracing the pin 25. By means of this thrust toggle, the switch-member will be moved into and out of engagement with its stationary contacts, and the direction of motion of the switch-member will be in substantially a straight line. A link 39, provided with a slot 41, adjacent one end thereof, is connected at its other end with the connecting-pin 35 of toggle 31, 33, by which to move 80 the toggle. An actuating-member is connected with the slotted end-portion of said link 39 and is here shown as an arm 45, extended radially from the hub 48 journaled in suitable bearings 49 on the plate 5, and 90 bearing a pin 43 adapted to move in the slot 41 of said link 39. The slotted link and radial arm together form another toggle which is connected with the aforesaid thrust toggle, and serves as an actuating toggle 95 therefor. By a turning movement of the hub in a clockwise direction and a corresponding movement of the radial arm, the slotted link will be moved to straighten the thrust toggle and cause a lifting movement 100 of the switch-member, and such movement will be continued until the pin on the arm is moved above a line intersecting the centers of the hub 48 and pin 35, at which time the radial arm will engage the limiting stop 60, 105 to be hereinafter described, to restrain further movement of the hub in a clockwise direction, thus locking the thrust toggle in a

nearly straightened position, whereupon the switch-member is held in engagement with its stationary contacts.

Similarly, the carrying frame 16 has ears 5 to 18 to which one end of a two-part lifting lever 22 is pivoted, as at 20, the other end of said lever being pivoted at 24 to the plate 5. A thrust toggle, comprising links 32, 34, pivotally connected together at 36, has 10 one of its links, as 34, pivoted at 38 to the plate 5, and its other link, as 32, loosely connected with the lifting lever at a point near the pivotal connection of said lever with the bracket, such loose connection being here 15 shown as a pin 30, arranged at the upper end of the link, which engages a pin 26 on the lifting lever, and a stirrup 28 supported on the pin 30 which embraces the pin 26. By means of this thrust toggle, the other 20 switch-member will be moved into and out of engagement with its stationary contacts, and the direction of motion of the switch-member will be in substantially a straight line. A link 40, provided with a slot 42 adjacent one end thereof, is connected at its other end with the connecting-pin 36 of toggle 32, 34, by which to move said toggle.

An actuating-member is connected with the slotted end-portion of said link 40 and is 25 here shown as an arm 46, extended radially from the hub 48 and angularly related to the arm 45. The slotted link 40 and radial arm 46 together form another toggle which is connected with the thrust toggle 32, 34, 30 and serves as an actuating toggle therefor. Said actuating toggle is designed to operate to control the switch-member in the same manner as the aforesaid actuating toggle controls the switch-member connected there- 35 with.

A fixed pin 60 is arranged on the ear, which is adapted to be engaged by either radial arm 45 or 46, when said arm is moved into position to operate the toggle to move 40 the switch-member into open circuit position.

It will be observed that the two radial arms are rigidly connected to the same hub, and therefore together form a bell-crank 45 lever by which to operate the two switch-members; and furthermore, on account of such rigid connection, the pin 60 may serve to limit movement of both arms, thereby to hold the toggles of either switch-member in 50 position to hold such switch-member in engagement with its stationary contacts, and the other switch-member out of engagement with its stationary contacts.

The hub 48 is provided with a suitable 55 recess 50 adapted to receive the end of a detachable operating-device, such as a wrench, whereby the hub may be turned in either direction, as may be required, to correspondingly move the radial arms and tog-

gles connected therewith and to operate the 60 switch-members.

Assuming the switch-mechanism to be in the position shown in Fig. 1, wherein one of the switch-members is in closed position and the other in open position, and it is 70 proposed to throw the switch into its other position, the hub 48 will be engaged by a switch handle or wrench and turned counter-clockwise, whereupon the pin in the radial arm 45 will be moved from the ends of the 75 slot in the slotted link 39 and thereby break the actuating-toggle formed by said arm and link, and the thrust-toggle which, in the closed position of the switch, is slightly 80 biased toward open position, will be collapsed by the weight of the switch-member, and the switch-member will consequently move into open position. If, for some reason, the switch remains in closed position after breaking of the actuating toggle, 85 then, when the actuating member is sufficiently rotated, the pin in the arm 45 will engage the other end of the slot in the link 39 and a further movement of the actuating member will operate to positively break the 90 thrust toggle and move the switch to open position. While the radial arm 45 is thus being moved to break the actuating-toggle and permit the opening of the switch-member connected therewith, as aforesaid, the 95 other radial arm 46 is being moved along the slot in the slotted link 40, and said slot is purposely made long enough to provide for continued movement of said radial arm 46, until the other switch-member has been 100 moved into open position, and at or about such moment the pin on said arm 46 will arrive at the inner end of said slot, and will begin to move the link, and such movement will be continued until the thrust-toggle has 105 been moved to nearly a straightened position, thereby to close the switch-member, and when so moved, the slotted link will be moved into toggle-locking position, and the radial arm 45 will be moved into engagement 110 with the pin 60, which arrests the movement. The relative positions of the toggle elements of the two switch-members are now reversed, and will be locked until again positively operated. It will be ob- 115 served that when throwing the switch, the closing switch-member is first moved into open position and then the open switch-member is moved into closed position, and that the slots in the components of the actuating-toggles admit of such independent and successive movements of the switch-members.

I claim:

1. In an electric-switch, two independent 125 movable switch-members, an actuating-member therefor, and toggle-mechanisms having slotted compartments independently opera-

- tively connecting said switch-members with the actuating-member, to permit of operation of one of said switch-members by said actuating-member independently of the 5 other.
2. In an electric-switch, two independent movable switch-members, an actuating member therefor, toggle mechanism independently connecting said switch-members with 10 said actuating-member, and means whereby said actuating-member will positively operate one of said members before acting to operate the other member.
3. In an electric-switch, the combination 15 of two independent movable switch-members, a thrust toggle associated with each switch-member, an actuating-means, and means connecting said toggles with said actuating-means arranged for the independent 20 operation of said switch-members upon operation of said actuating-means.
4. In an electric-switch, the combination 25 of two switch-members, means to cause said members to move in an approximate straight line, a thrust-toggle associated with each member, an actuating-member, and slotted links connecting said toggles and said actuating-member to permit the operation of one of said switch-members independently 30 of the other.
5. A double-throw switch comprising in combination two switch-members, an actuating-member, two radial arms connected with said actuating-member, a pin carried 35 by each of said arms, a thrust toggle associated to each of said switch-members, a link operatively connected to each of said toggles, and a slot in each of said links in operative engagement with each of said pins, 40 said arrangement forming means whereby said switch-members may be alternately operated by said actuating-member.
6. An electric-switch comprising in combination a switch-member, a thrust-toggle 45 associated with said member, a second thrust-toggle in operative connection with said first thrust-toggle, and means associated with said second toggle to admit of restricted relative longitudinal displacement 50 of the members of said second toggle independent of the members of said first toggle.
7. In a double-throw electric-switch, the combination of two switch-members, a thrust 55 toggle for each member, a second thrust toggle connected with each of the aforesaid thrust toggles including a slotted link, arms with pins engaging the slots in the links, and an actuating-member to which said arms are connected.
8. In a double-throw electric-switch, the 60 combination of two switch-members having a straight-line motion, a thrust toggle for each member, a second thrust toggle connected with each of the aforesaid thrust toggles including a slotted link, arms with pins 65 engaging the slots in the links, and an actuating-member bearing said arms, said arms being angularly related to each other.
9. In a double-throw electric-switch, the 70 combination of two switch-members having a straight-line motion, a thrust toggle for each member, a second thrust toggle connected with each of the aforesaid thrust toggles including a slotted link, arms with pins 75 engaging slots in the links, and a rotatable actuating-member to which said arms are connected.
10. In a double-throw electric-switch, the 80 combination of two switch-members having a straight-line motion, a thrust toggle for each member, a second thrust toggle connected with each of the aforesaid thrust toggles including a slotted link, arms with pins 85 engaging slots in the links, and a rotatable actuating-member to which said arms are connected, having actuating-means adapted to receive an operating-device by which to rotate said member, the said arms being angularly related to each other. 90
11. In a double-throw electric switch, the combination of two independent movable switch-members, an actuating-member therefor, and means operable to independently move said movable switch-members between open and closed positions arranged for the simultaneous disposition of both movable switch-members in full open position. 95

In testimony whereof, I have signed my name to this specification in the presence of two subscribing witnesses.

GEORGE A. BURNHAM.
